UNITED STATES PATENT OFFICE

2,499,191

VERTICAL LOOP FURNACE

Norman B. Jones, Ballston Lake, and James L. McFarland, Schenectady, N. Y., assignors to General Electric Company, a corporation of New York

Application September 22, 1948, Serial No. 50,538

1 Claim. (Cl. 263—3)

1 Our invention relates to annealing furnaces of the type adapted for the continuous heat treating of thin strip material, such as steel strip, particularly where the surface of the strip to be annealed is bright or highly polished and must not be oxidized or scratched in the process. It is the object of our invention to provide an improved furnace of this type which is suitable for heating strip to temperatures as high as 2300° F., or more.

Our furnace is the vertical loop type, utilizing what might be called a vertical catenary loop. That is the loop is in the shape of a catenary with the open end turned upward and the vertical length of the catenary is greater than its width horizontally. Previous vertical loop furnaces such as that disclosed in United States Patent No. 2,009,856, granted to Albert N. Otis and James L. McFarland on July 30, 1935, have utilized straight loops; that is, loops approximately semi-circular in form, with the strip entering and leaving the loop vertically. One advantage of the vertical loop construction is that the tension on the strip is lowest at the point of highest temperature which is at or near the bottom of the loop. Our vertical catenary loop furnace retains this advantage and at the same time, because of the greater stability of a catenary loop plus the stepped type construction employing a plurality of heating chambers, and other features of our furnace described later in more detail, it is unnecessary to use supports or seals of any kind touching the strip while it is in the heating section of the furnace.

Other furnaces employing a catenary loop are known, for example, that disclosed by United States Patent No. 2,060,634, granted to Albert N. Otis on November 10, 1936, but they use a flat catenary, that is, a catenary with a horizontal dimension much greater than the vertical dimension, representing in effect merely a sag in the strip as it passes through the furnace. In contrast it is an object of our invention to employ a vertical catenary loop with the vertical dimension greater than the horizontal in order to minimize the stress on the strip at the center portion of the catenary at the bottom of the loop where the temperature is the highest.

Our invention will be better understood from the following description taken in connection with the accompanying drawing, and its scope will be

pointed out in the appended claims. In the drawing, Fig. 1 is a side view, partly in section, of one embodiment of our invention and Fig. 2 is a sectional view along the line 2—2 of Fig. 1.

5 In Fig. 1 of the drawing, the strip which is to receive the heat treatment is represented at 1. This strip may be withdrawn from a coil (not shown) and fed to the furnace by means of the pinch rolls 2 and is finally withdrawn from the furnace by the pinch rolls 3, the two sets of rolls being driven by suitably synchronized driving means, whereby the strip is driven at the same speed by each set. The strip first passes over an idler roller 4 as it enters the heating section 10 of the furnace, which idler roll supports one end of the vertical catenary loop.

As the strip 1 passes through the furnace, it passes first through a catenary shaped heating section which is composed of 7 interconnected chambers in the particular construction illustrated. The heating section is composed of entrance chamber 5, heating chambers 6, 7, 8 and 9, chamber 10, and exit chamber 11. Each of the 20 chambers has an outer metal casing 12, a layer of heat insulating material 13, and an interior lining 14 of suitable heat refractory material. Adjacent the side walls of chambers 6, 7 and 9 are provided electric heating elements 15 to maintain each chamber at the desired temperature. 25 The lowest heating chamber 8 which surrounds the bottom portion of the catenary loop has electric heating elements 15 on the side and bottom walls. Chamber 8 is the chamber having the 30 highest temperature which, for example, may be approximately 2300° F.

The outer walls of chambers 6, 7 and 9 are supported in elevated position by structural steel framework 16. The inner walls of these three 35 chambers are supported by refractory arches 17 which also form a part of the interior refractory lining of the next lower chamber in each case. Entrance chamber 5 is supported principally by heating chamber 6. Exit chamber 11 is supported principally by chamber 10 which in turn is supported principally by heating chamber 9. Heating chamber 8 is supported on I-beams 18. There are vertical members 19 on both sides of the heating section to provide additional support 40 for all chambers.

The use of a plurality of chambers following the contour of the strip being heated, as illustrated by Fig. 1 gives a number of advantages over a furnace having a single heating chamber. It allows the walls to be broken up into relatively small sections. This decreases the unit stress on the brick or other heat refractory material 14, a factor which is highly important at temperatures of 2300° F., since it is well-known that the crushing strength of refractory materials in common use today is greatly reduced at such a high temperature. The use of a plurality of chambers also requires a minimum of wall area for a given strip length, thus permitting maximum economy in the use of refractory and other material. A further advantage is that the heating elements follow closely the contour of the strip which gives improved efficiency and more accurate temperature control. Also, with this construction the strip is not touched by supports or seals of any kind while it is in the heating section of the furnace; hence, it cannot be scratched from this cause. By the time the strip reaches exit roller 21 its temperature is reduced sufficiently that it will not be scratched by the roller.

On the exit side of the heating section of the furnace, chamber 11 is provided with adjustable radiation baffles 19 to aid in confining the heat to the heating chambers. It is also provided with a blower 20 of the type disclosed in United States Patent No. 2,195,310, granted to Allen G. Hotchkiss on March 26, 1940, to prevent or at least partially counteract the flow of the protective atmosphere, or other gases if no protective atmosphere is used, out of the heating chambers and into the subsequent cooling section of the furnace. It is customary to equip high temperature electric furnaces of this type with means for providing an artificial non-oxidizing protective atmosphere utilizing such gases as hydrogen, a mixture of hydrogen and oxygen, or atmosphere converter gas which is made by burning suitable natural or manufactured gas with a controlled deficiency of air. Such furnaces are occasionally operated without an artificial protective atmosphere, however, for some kinds of material. Our invention is suitable for application to furnaces with or without artificial protective atmosphere.

As the strip leaves the chamber 11 it passes over a roll 21, which supports the other end of the vertical catenary loop in the heating section, thence over a second roll 22 and into cooling section 23. The cooling section is composed of two vertical chambers, as shown in Fig. 1. The strip passes downward in the left chamber, beneath rolls 24 and 25 at the bottom of the cooling section, upward in the right chamber, over roll 26 and out of the furnace through pinch rolls 3. While the embodiment of our invention illustrated in the attached drawing employs only one cooling section, two or more cooling sections may be used, if necessary, to provide the strip with the desired characteristics. The cooling section is provided with both electric heating elements 27 and pipes 28 extending across the chambers at spaced points. Cooling fluid, such as air or water, is circulated through pipes 28 and by correlating the cooling action of these pipes and the heat supplied to the chambers by heaters 27 the cooling of strip 1 may be accurately controlled.

In the operation of this furnace, a suitable control means (not shown) is utilized to maintain the proper tension on the strip in order to maintain the vertical catenary loop. One suitable

control means is disclosed by the above-mentioned United States Patent No. 2,060,634, granted to Albert N. Otis. In the system of this patent, means are provided for adjusting the speed of the outgoing pinch rolls 3 with relation to the speed of the incoming pinch rolls 2 in order to maintain the loop in the heating section of the furnace at the desired height. While pinch rolls 2 and 3 operate at approximately the same speed, it may be necessary to vary the speed of rolls 3 slightly with respect to rolls 2 because of slight variations in construction of the two motors which drive the rolls and of the rolls themselves, differences in temperature of the strip engaged by the two sets of rolls, and particularly, the elongation of the strip due to its higher temperature at the point of leaving the furnace than at the entrance point. In certain cases it may be found desirable to drive one or more of rolls 4, 21 and 22; these rolls along with rolls 24, 25 and 26 are shown as idler rolls on the attached drawing.

Fig. 2 of the accompanying drawing is a sectional view along the line 2-2 of Fig. 1, showing details of the construction of heating chamber 8. Refractory arch 17, which supports the inner walls of heating chambers 7 and 9, can be clearly seen in this view. Fig. 2 also illustrates additional details of the construction of blower 20.

While we have chosen the particular embodiment described above as illustrative of our invention, it will be apparent that various other modifications may be made without departing from the spirit and scope of our invention, which modifications we intend to cover by the appended claim.

What we claim as new and desire to secure by Letters Patent of the United States is:

40 A vertically disposed furnace for heating moving strip material while it is suspended in the form of a catenary loop comprising, a plurality of interconnected heating chambers disposed along the contour of said catenary loop, the enclosed 45 closures of said heating chambers being in close proximity to but not in contact with said strip material, said heating chambers being arranged so that said strip material passes consecutively through said heating chambers, each heating 50 chamber enclosure comprising an outer metal casing, a layer of heat insulating material within said metal casing and an interior lining of heat refractory material within said layer of insulating material, an internal arch of refractory material in each heating chamber except the topmost chamber on each leg of the catenary for supporting in part the heating chamber immediately above each such chamber, heating means in said heating chambers, an entrance chamber 55 mounted on one of said topmost heating chambers and supported principally thereby and interconnected in strip conducting relation therewith, an exit chamber mounted on the other of said topmost heating chambers and supported principally thereby and interconnected in strip conducting relation therewith, an entrance roll in said entrance chamber for supporting one end of said catenary loop, and an exit roll in said exit chamber for supporting the other end of said 60 catenary loop.
